GLAZIER'S POINT SETTER

Donald J. Harris, Deer Lodge, Mont.

Application October 15, 1948, Serial No. 54,758

6 Claims. (Cl. 1—44)

1

This invention relates to new and useful improvements and structural refinements in glazier's point setters, and the principal object of the invention is to provide a power operated setter of the character herein-described, such as may be conveniently and effectively employed for dispensing and driving glazier's points with the expenditure of a minimum amount of effort on the part of the operator.

This object is achieved by embodying in the structure of the setter a solenoid having a reciprocable armature which, in turn, is operatively engageable with the point setting mechanism, so that the setting or driving operation may be effected by simply depressing a switch so as to energize the solenoid.

An important feature of the invention involves the provision of resilient means for returning the point setting mechanism as well as the armature of the solenoid to their initial positions in readiness for the next point setting operation.

Some of the advantages of the invention reside in its simplicity of construction, convenience of operation, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention.

Figure 2 is a longitudinal cross sectional view thereof, showing the same in use.

Figure 3 is an end view looking to the right of Figure 1.

Figure 4 is a perspective view of a point engaging and setting member used in the invention.

Figure 5 is a perspective view of a solenoid supporting bracket used therein, and

Figure 6 is a fragmentary perspective view showing an end portion of a base plate used in the invention.

Like characters of reference are employed to designate like parts in the specification and throughout the several views.

Referring now to the accompanying drawings in detail, the invention consists of a glazier's point setter designated generally by the reference character 10, the same embodying in its construction an elongated base plate 12, one end portion of which is provided with a longitudinally extending, channel-shaped guide 14 having an open outer end, as is best shown in Figure 6.

A solenoid designated generally by the reference character 16 is mounted on the base plate 12, this solenoid including in its construction a cylindrical shell 18 containing a suitable wind-

2

ing 20 which, in turn, is supported by a stationary tubular core 22 as is best shown in Figure 2. The core 22 as well as the shell 18 are supported by a pair of end plates 24, 26, these end plates being preferably formed with integral, horizontally angulated brackets 28, 30 respectively, as will be clearly apparent. The bracket 30 of the end plate 26 is secured to the base plate 12 as at 32, while the bracket 28 of the end plate 24 is secured to the base plate by a pair of screw threaded, up-standing rods 34 provided with nuts 36. It is to be noted that the rods 34 pass through suitable apertures 38 with which the bracket 28 is formed and engage at their lower ends a pair of screw threaded apertures 39 provided in the base plate, as illustrated in Figure 6.

It is to be also noted that the bracket 28 is disposed in a position where it overlies the guide 14 in the base plate 12, and that it is formed with a longitudinally extending slot 40 and with a diamond-shaped opening 42, the purpose of which will be hereinafter more fully described.

A vertical point magazine 44 having a diamond-shaped cross sectional configuration conforming to the configuration of the point with which the invention is to be used, has the lower end portion thereof secured by welding, or the like, in the opening 42 of the bracket 28, a transversely extending reinforcing strap 46 being welded or otherwise secured to an intermediate portion of the magazine 44 and also being secured by suitable lock nuts 48 to the upper end portions of the aforementioned rods 34, as is best shown in Figures 1 and 3. By virtue of this arrangement the magazine 44 is securely retained in a substantially upright position, and it is to be understood that the lower end of the magazine is in communication with the guide 14 in the base plate 12, so that the points 50 may be individually and successively discharged from the magazine into the guide 14, as will be apparent from reference to Figure 2. The points 50 are adapted to be stacked in the magazine 44, and a follower 52, assuming the form of a simple strap slidable in the magazine, is employed for urging the points 50 downwardly into the guide 14, this being effected by providing the follower 52 with a laterally projecting ear 54 and anchoring a tension spring 56 at one end to this ear, while the remaining end of this spring is anchored to the aforementioned reinforcing strap 46 as at 58.

A point engaging and driving member 60, best shown in the accompanying Figure 4, includes a substantially horizontal portion 62 which is slidable in the guide 14 of the base plate 12 and also includes an upstanding intermediate portion 64 terminating in an angulated upper extremity 66.

The horizontal lower portion 62 of the member 60 is recessed as at 68 and is provided with a

substantially V-shaped notch 70, this notch being adapted to engage and receive therein approximately one-half of a point 50 after it is discharged from the magazine 44 into the guide 14. The recess 68 assures that the thickness of the bottom 72 of the recess is substantially equal in thickness to the point 50, so that only one of the points is engaged by the notch 70 at one time, that is, so that only the lowermost of the points 50 is engaged by the notch 70 when the member 60 is slid in the direction of the arrow 74 (see Figure 1) in order to drive the point into the work.

Similarly, the guide 14 in the base plate 12 is provided with a substantially thin bottom wall, so that the point setter may be disposed as close as possible to the work, as indicated in Figure 2.

Referring again to the aforementioned solenoid 16, the stationary tubular core 22 thereof projects at one end from the shell end plate 26 and contains a reciprocable armature 76, the outer end portion of which is formed with a bore 78 accommodating a tension spring 80. This spring is anchored at its inner end as at 82 to the armature 76, while the outer end of the spring is anchored to a transverse pin 84 provided in the core 22, the pin 84 also functioning as a stop for the armature 76 which is normally urged by the spring 80 in the direction of the arrow 86 in Figure 2.

The inner end of the armature 76 is formed with a diametrically extending keeper notch 88 configurated as is best shown in Figure 2, this keeper notch being releasably engageable with a substantially U-shaped tongue 90 which is wrapped around and secured to the angulated upper end portion 66 of the aforementioned member 60 by means of a suitable rivet, or the like, 92.

The outwardly projecting end portion of the core 22 is provided with a longitudinal slot 94 in which is slidable a laterally projecting pin 96 provided on the armature 76, whereby the armature is free to slide longitudinally in the core 22 but is prevented from rotating therein, as will be clearly apparent. In this manner, assurance is had that the tongue 90 is always aligned with the notch 88, so that the tongue is readily receivable in the notch when the armature 76 is driven as indicated at 98 in Figure 2, upon energization of the solenoid 16.

It may be explained at this point that the tongue 90 is preferably formed from non-magnetizable material, so that the aforementioned member 60 is not affected by residual magnetism in the armature 76.

The solenoid 16 receives its supply of electric current through a conductor 100 and a suitable switch 102, and as will be readily apparent, upon energization of the solenoid, the armature 76 thereof will be driven in the direction of the arrow 98 so that the tongue 90 is engaged by the notch 88 of the armature, after which the armature together with the member 60 will be driven in the direction of the arrow 98 so that the notch 70 of the member 60 is brought in engagement with the lowermost of the points 50 and the lowermost point is driven into the frame 104 of the work. This is best shown in Figure 2, wherein the reference character 106 indicates a glass panel which is to be installed in the frame 104 and 70 which is being secured in position by the points 50.

Finally, it may be explained that an intermediate portion 64 of the member 60 extends slidably through the slot 40 of the bracket 28, and 75

suitable spring 108 has one end portion 110 thereof secured or anchored to one of the aforementioned rods 34, while its remaining end portion 112 bears against the member 60, whereby the member 60 is returned to its initial position as soon as the solenoid 16 is deenergized and in readiness for the next cycle of operation.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction and arrangement of parts may be resorted to without departing from the spirit and scope of the invention as claimed.

Having described the invention, what is claimed as new is:

1. In a glazier's point setter, the combination of a base provided at one end portion thereof with a channel-shaped guide, a point magazine mounted above said guide and adapted to discharge points into the latter, a point engaging and setting member slidable in said guide, and a solenoid mounted on said base and including a reciprocable armature operatively engageable with said member whereby points may be individually and successively expelled from said guide upon energization of said solenoid.

2. A glazier's point setter comprising a base provided at one end portion thereof with a channel-shaped guide having an open outer end, a solenoid mounted on said base and including a reciprocable armature, a point engaging and setting member including a lower portion slidable in said guide and an upper portion operatively engageable by said armature, a bracket provided at one end of said solenoid and overlying said guide, said bracket being formed with a slot to slidably accommodate an intermediate portion of said member, and a point magazine carried by said bracket and communicating with said guide whereby points discharged therefrom may be engaged by the lower portion of said member and driven outwardly from the open end of said guide.

3. The device as defined in claim 2 together with resilient means for urging said member toward the inner end of said guide.

4. The device as defined in claim 2 wherein said solenoid includes a stationary tubular core slidably receiving said armature, and resilient means for urging said armature toward one end of said core.

5. The device as defined in claim 2 wherein one end portion of said armature is formed with a keeper notch, the upper end of said member being provided with a tongue separably engageable with said notch.

6. The device as defined in claim 5 wherein said tongue is formed from non-magnetizable material.

DONALD J. HARRIS.
